UNITED STATES PATENT OFFICE.

ALLAN D. SHAW, OF SAVANNA, ILLINOIS.

INTERNAL-COMBUSTION ENGINE.

1,097,947.

Specification of Letters Patent. Patented May 26, 1914.

Application filed January 2, 1913. Serial No. 139,857.

To all whom it may concern:

Be it known that I, ALLAN D. SHAW, a citizen of the United States, residing at Savanna, in the county of Carroll and State 5 of Illinois, have invented certain new and useful Improvements in Internal-Combustion Engines, of which the following is a specification.

This invention comprehends improvements in internal combustion engines and relates more particularly to those of the four-cycle type.

The primary object of the invention resides in the provision of an engine of this 15 nature wherein sliding sleeve valves surround the pistons and sliding port covers are employed to open and close the intake and exhaust ports and operate in conjunction with the sleeve valves to reduce the loss 20 of power, due to poor compression and premature escape of burned gases, to the minimum.

The invention also aims to provide novel 25 valve actuating means including crank shafts connected by links to port covers, said crank shafts carrying cams which actuate levers connected to the sleeve valves.

With these and other objects in view, as 30 will become more apparent as the description proceeds, the invention consists in certain novel features of construction, combination, and arrangement of parts, as will be hereinafter described and claimed.

For a complete understanding of my invention, reference is to be had to the following description and accompanying drawings, in which:

Figure 1 is a longitudinal sectional view 40 through one cylinder of my improved engine, the piston and parts of the valve actuating means being shown in elevation, Fig. 2 is a transverse sectional view taken upon the plane of line 2--2 of Fig. 1, Fig. 3 is a view taken upon a plane at right angles to Fig. 1, the parts being shown partly in elevation and partly in section, Figs. 4, 5 and 6 are longitudinal sectional views, showing somewhat diagrammatically the positions of 45 the movable parts at the beginning of the

exhaust, intake, and compression strokes, respectively.

In the following description and accompanying drawings, similar parts will be referred to and designated by like reference 55 characters.

Referring in detail to the drawings by numerals, 10 designates the working cylinder, which is formed with the usual water channels 11 and which is formed integral 60 with a head 12, said head having formed therein the annular water chamber 13 and forming a grand shoulder 14, the purpose of which will be hereinafter explained. The head is enlarged in diameter, as at 15, and 65 formed with the annular flange 16, said flange being secured by means of suitable fasteners 17, to a water jacket casing 18, said casing being formed with the water channels 19. The inner end of the casing 18 70 is provided with a flange 20, which is suitably secured to the crank case 21.

The working cylinder 10 is formed adjacent the cylinder head 12 with the intake port 22 and the exhaust port 23, said ports 75 coinciding respectively, with an intake opening 24 and an exhaust opening 25, formed in the water jacket casing 18.

A sleeve valve 26 slides within the working cylinder 10 and is ground upon its outer 80 edge to form a tight fit with the ground shoulder 14. The sleeve 26 is suitably actuated to open and close the intake and exhaust ports, by means of links 27 pivotally connected between ears formed upon the 85 sleeve valve and pivotally connected at their ends to levers 28 and 29. The levers are pivoted intermediate their ends to brackets, generally designated 30, and including cylindrical body portions depending from the 90 crank casing 21 and arms 32 formed integral with said body portions. The levers 28 and 29 have secured to their outer ends sockets 33 to which are pivotally connected guide rods 34, said guide rods sliding within bores 95 35 formed in the body portions of the brackets. Expansive spiral springs 36 surround the rods 34 and bear against the sockets 33 and the inner ends of the body portions 31 of the brackets.

- The expansive springs 36 hold the levers 28 and 29 rigid with half time crank shafts 39 and 40, said crank shafts being actuated by intermeshing gears 41 and 42, which meshes with one of said first mentioned gears. The small gear 42 is rigid with the main crank shaft 43 to which is connected the pitman 44, which actuates the piston 45.
10. Semi-cylindrical port covers or plates 46 and 47 are slidable between the cylinder and head, and the water jacket casing 13. The intake port cover 46 is formed with an opening 48 adapted to register with the ports 22 and 24 and the exhaust port cover 47 is formed with an opening 49 adapted to register with the exhaust ports 23 and 25. The inner ends of the port covers are connected by means of pivoted links 50 to the cranks of the half time shafts 39 and 40.
- Upon reference to Fig. 3, the relative positions of the cams and links 50 will be readily perceived. When the engine is about to fire, the various parts are positioned, as shown in Fig. 1, at which time it will be noted that the sleeve valve 26 is in contact with the ground shoulder 14 and the port covers are in such positions as to close the intake and exhaust ports, thus co-operating with the sleeve valve to prevent a premature loss of the exploded gas. When the piston is at the extremity of the power stroke, the sleeve 26 will have been moved inwardly through the medium of the links 27, and levers 28 and 29 so as to open the ports 22 and 23. The levers 28 and 29 are actuated by the cams 37 and 38, respectively, which latter are moved by the half time shafts 39 and 40, said shafts being actuated by the gears 41, which in turn are actuated by the gear 42. While the sleeve 26 has been moving inwardly, the port covers have been moving in the same direction under the influence of the half time shafts 39 and 40 and the links 50, so that at the end of the power stroke, the exhaust openings are in registration but the intake is interrupted by the port cover 46, which arrangement is shown in Fig. 4.
50. The exhaust port remains open sufficiently long to allow the piston during its scavenging stroke, to clear the cylinder or rather the sleeve 26 of the burned gases. When the intake stroke begins the exhaust passage has been interrupted by an outward movement of the port cover 27 and the intake passage has been opened by a further inward movement of the port cover 26 and the ports are positioned, as shown in Fig. 5. It is to be understood that the cams 37 and 38 are so designed as to cause a proper timing of the sleeve valve 26 in conjunction with port covers 46 and 47. At the beginning of the compression stroke the parts are raised, as

shown in Fig. 6, and it will be noted that the sleeve 26 is in contact with the ground shoulder 14 and that the port covers have closed the intake and exhaust passages, thus causing a maximum compression. The longitudinal edges of the port covers contact with each other and are ground to form a perfect joint.

It will be seen from the foregoing description in connection with the accompanying drawings, that I have designed an improved internal combustion engine in which the leakage during the compression and power periods, is practically eliminated, thus greatly increasing the efficiency of the engine. The cylinder head and cylinder may be easily and quickly removed to permit access to the piston, valve, and port covers, and the construction of said piston and head as well as the construction of the water jacket casing maintain the working parts at the proper temperature. The engine can be manufactured at a minimum expense since there are no complicated parts and the design is such that the larger the bore of the cylinder, the less in proportion the mass of the engine, as the same thickness of cylinder wall, cylinder head, port covers, and outside casing, can be used in a large engine. The engine is noiseless in operation and the valve actuating means are of such a design as to insure perfect working of the various movable parts.

It is to be understood that while I have shown and described the preferred embodiment of my invention, I do not wish to be limited to this exact construction, combination, and arrangement of parts, but may make such changes as will fall within the spirit and scope of the invention.

Having thus described my invention, what I claim is:

1. In an internal combustion engine, a cylinder, a sleeve valve slidable against the interior of the cylinder, plate valves slidable against the exterior of the cylinder, and a casing surrounding the plate valves in engagement with their exterior faces, the cylinder and casing being formed with channels to receive a cooling medium, whereby both sides of the plate valves and the exterior of the sleeve valve are cooled.
2. In an internal combustion engine, a cylinder, a sleeve valve slidable within said cylinder, plate valves slidable upon the exterior of the cylinder, a casing surrounding the plate valves in engagement therewith, whereby the last mentioned valves are guided, means for supporting the casing, and an annular flange formed upon the cylinder for engagement with the upper edge of the casing to support the cylinder.
3. In an internal combustion engine, a cylinder, a cylinder head provided with a

ground shoulder, a water jacket casing surrounding said cylinder head and being spaced therefrom, the cylinder and casing being formed with registering ports, port 5 covers slidale between the cylinder and casing and adapted to close said ports, and a sleeve valve slidale within the cylinder for engagement with said ground shoulder, at which time said ports are closed, the sleeve

valve and port covers coöperating to insure 10 a maximum amount of compression.

In testimony whereof I affix my signature in presence of two witnesses.

ALLAN D. SHAW.
